LAMP ELEMENT AND METHOD OF MAKING
SAME

Chester H. Fulp, Chicago, Ill.

Application December 21, 1939, Serial No. 310,319

13 Claims. (CL. 176—40)

This invention relates to improvements in a lamp element and a method of making the same, the element including a filament of the character of a resistance coil which, while highly desirable for use in connection with incandescent lamp filaments, may also be desirable with other electrical devices, as will be apparent to one skilled in the art.

In many cases, such, for example, as traffic signal lights, it is highly desirable to use a multi-filament incandescent lamp so that if one filament burns out, the particular lamp is not totally darkened but will operate with a goodly portion of its illuminating efficiency on the remaining filament or filaments. I am aware that in the past many and various designs for incandescent lamps having two or more filaments have been developed, but in no instance of which I am aware have these formerly known devices been capable of sufficiently economical manufacturer to warrant a wide commercial usage.

With the foregoing in mind, it is an important object of the present invention to provide a multi-filament lamp element which may be manufactured at only a negligible increase in cost over the cost of manufacture of a single filament incandescent lamp.

A further object of the invention is the provision of a lamp element embodying more than two filaments, in which the filaments may be assembled with the lead-in wires by very simple attaching operations and without the necessity of any especially designed machines to accommodate the novel construction.

Another object of the invention is the provision of a triple-filament lamp element in which the triple-filament may be attached to the lead-in wires by four simple clamping operations.

Another feature of this invention is the provision of a lamp element embodying an integral segmented filament arranged so that each segment functions as an individual filament.

It is also a feature of this invention to provide a multi-filament lamp element in which the filament coils are so arranged as to have the effect of a closed magnetic field, and which operates with an extremely high efficiency even after the destruction of a single filament.

A further object of the invention is the provision of a resistance element having at least three resistance segments so arranged as to provide the effect of a completely closed magnetic field between any two of the segments.

Still another feature of the invention resides

in the provision of a resistance element adapted for use as a multi-filament for an incandescent lamp so arranged that the magnetic field set up by each filament is in a direction from the same lead-in wire to the other.

Still a further object of the invention is the provision of a new and novel method of making a multi-filament lamp element.

While some of the more salient features, characteristics and advantages of the present invention have been above pointed out, others will become apparent from the following disclosures, taken in conjunction with the accompanying drawings, in which:

15 Figure 1 is a side-elevational view of an incandescent lamp containing a lamp element embodying features of the present invention and constructed in accordance with the novel method forming a part of this invention;

20 Figure 2 is an enlarged, fragmentary, perspective view of the lead-in wires included in the lamp element of Figure 1;

25 Figure 3 is an enlarged, exploded view of a triple-filament lamp, indicating one method of construction of such a triple-filament;

Figure 4 is a greatly enlarged view of the preferred form of filament for the lamp of Figure 1;

30 Figure 5 illustrates the lamp filament before attachment to the lead-in wires;

Figure 6 illustrates the first method step in the assembling of the lamp element;

Figure 7 illustrates a succeeding step in the formation of the lamp element;

35 Figure 8 indicates the next advanced step in the practice of my novel method; and

Figure 9 illustrates the final step in the making of the lamp element.

As shown on the drawings:

40 It will be appreciated that in the drawings the filament coil and lead-in wires are greatly exaggerated for the purpose of clarity, to better illustrate the winding of the filament coil and the clamping formation provided on the inner ends of the lead-in wires. This exaggeration is especially true in connection with the showing of the inner end formations on the lead-in wires, and it will be readily understood that the clamping portions of these wires need not be of as large a proportional size as illustrated.

45 In the illustrated embodiment of this invention, there is shown an incandescent lamp including the usual base 10, the transparent envelope or bulb 11, with the stem 12 carrying the button rod 13 terminating in the usual button

14, all within the base and envelope. Supported within the stem 12 in a known manner and extending upwardly on either side of the button rod are the lead-in wires 15 and 16 respectively. These lead-in wires make contact with the customary contact points on the base in a well-known manner. Carried on the inner ends of the lead-in wires 15 and 16 and also aided by any supports, if desired, associated with the button 14 is my novel multi-filament element 17. Herein and in the appended claims, where the term "lamp element" is used, such term is to be construed as referring to my novel arrangement and connection of lead-in wires and filaments.

In the modern manufacture of incandescent lamps, it is customary to provide a bent portion in the end of a lead-in wire, so that it may be clamped to the filament and thus support the filament and establish electrical connection between the filament and lead-in wire. In the present invention, each lead-in wire is preferably provided with a plurality of clamping portions. In the illustrated instance, with reference more particularly to Figure 2, it will be seen that the lead-in wire 15 is provided with a lateral reverse bend 18 and also a vertical reverse bend 19, each forming a clamping portion. The legs of each of the clamping portions 18 and 19 may be squeezed together over a part of the filament wire to join the filament to the lead-in wire. The other lead-in wire 16 is provided with a similar outwardly and laterally extending clamping portion 20 and a vertically extending clamping portion 21. For convenience in assembly, it is preferable to have the free leg of the vertical portion 19 extending in the opposite direction to the free leg on the vertical portion 21, as exemplified in the showing in Figure 2. The bent clamping formations on each lead-in wire may be readily provided with a jig arrangement in an economical manner.

While a two-filament lamp is highly desirable, a three-filament provides much greater efficiency upon the burning out of a single filament. With the present invention, the cost of providing a three-filament arrangement is not only a negligible increase over the cost of a two-filament arrangement, but is also only negligibly more expensive than the provision of a single-filament arrangement. It will be especially understood, and more apparent later herein, that with the present invention, a three-filament arrangement may be provided with considerably more economy than most two-filament arrangements known heretofore.

One way of providing a three-filament arrangement is illustrated in Figure 3, wherein three separate filament coils 22, 23 and 24, respectively, are shown. The filament coils 22 and 24 are preferably substantially semi-circular, and the coil 23 extends across the loop formed by the coils 22 and 24 when they are joined together. With this arrangement, it is preferable to weld or similarly unite the adjacent termini of all three filaments on each side of the loop formed by the coils 22 and 24. The joined termini may then be clamped or otherwise attached to a lead-in wire. The center or cross-filament 23 may be either substantially S-shaped, as shown, or may bow upwardly or downwardly. The deviation from a straight line of this particular filament is only due to simplicity in manufacture by winding all of the filament coils with the same number of turns. It is preferable to have all the filament coils of the same resistance value so, if desired,

the central filament 23 could be of different material, or the turns could be made more numerous so that this filament would extend straight across the loop formed by the coils 22 and 24. This procedure of providing a three-filament arrangement is objectionably expensive in the manufacture of lamps for most commercial purposes.

In Figures 4 and 5, I have illustrated my preferred form of a three-filament arrangement, which is generally indicated by numeral 17. The structure 17 might be better termed an integral segmented filament. It preferably consists of a single integral coil having a terminus 25 at one end, a coil segment 26, an uncoiled portion or joint 27, a second coil segment 28, another joint 29, a third coil segment 30, and a final terminus 31. For purposes of economy, the segments 26, 28 and 30 are preferably of equal size and have the same number of turns so that all are of the same resistance value. The joints 27 and 29 are readily provided during the winding of the filament coil by simply skipping a turn at these particular points. In the resultant lamp assembly, each of the segments 26, 28 and 30 forms an individual lamp filament, and it will be appreciated that economy in manufacture is greatly enhanced by making all three filaments at one time as an individual unit and in handling a single piece of material while forming the ultimate three-filament arrangement and connecting the same to the lead-in wires.

My novel method of making a lamp unit embodying the lead-in wires and filament arrangements includes the method of attaching the filament arrangement to the lead-in wires, as illustrated in Figures 6 to 9, inclusive. All of the steps illustrated in these figures may be carried out on lamp manufacturing machines now in existence and do not require the development of special new machinery for the purpose of assembling the lamp element.

The first step in the assembly is shown in Figure 6, and there it will be seen that the terminus 25 is clamped in the formation 18 by compressing the legs of this formation together upon the terminus. The filament coil 26 is next formed substantially in the nature of a half-circle, the filament being longer than the distance between the lead-in wires, and the joint 27 is clamped in the formation 20 on the other wire 16, as seen in Figure 7. The following step consists in bending the filament coil 28 substantially in the form of a half-circle opposite the coil 26 to substantially complete the loop, and clamp the joint 29 in the formation 19 on the wire 15. The final step consists in disposing the filament coil 30 in the illustrated S-shape, or otherwise, across the loop formed by the coils 26 and 28, and clamping the final terminus 31 in the formation 21 on the wire 15. It is therefore apparent that with four simple clamping operations, a three-filament arrangement is provided, and in the assembly operation only two more simple clamping operations are necessary over the two operations necessary for the attachment of a single filament.

With reference to Figure 4, which shows a greatly exaggerated view of the triple-filament arrangement in final position, it will be seen that with all the coil segments 26, 28 and 30 having turns in the same direction, the magnetic fields set up by these coils all will pass along the respective coil from left to right as seen in this figure, assuming that the current enters through the lead-in wire 15 and departs through the

lead-in wire 16. The terminus 25 is connected to the lead-in wire 15, and consequently the magnetic field resulting from energization of the filament 26 will be along this filament to the connection of the joint 27 with the lead-in wire 16. Likewise, the magnetic field in the filament 28 will be from the joint 29 to the joint 27. Finally, the magnetic field in the middle filament 30 will be from the joint 28 to the terminus 31 or the lead-in wire 16. It will be noted that these magnetic fields approximately buck each other. Bearing in mind the fact that the showings of the clamping arrangements on the lead-in wires 15 and 16 are greatly exaggerated, it will be seen that substantially closed loops are provided between any pair of filament coils. In the event two filament coils burn out, the lamp will not fail, but some illumination will still be provided by the remaining coil. Consequently, if the lamp is used in traffic signals or the like, there is ample time for replacement before ultimate failure of the lamp and still have the signal operating properly until replacement is finally made.

It will be appreciated that the particular filament arrangement may be utilized in connection with other and various devices and incandescent lamps, such as resistance coils, heating coils, etc. It will further be noted that with this arrangement many undesirable effects in the circuit are eliminated, and the element is substantially unresponsive to outside disturbances so that it may be desirable for use in the form of miniature or larger elements in radio and television work.

It will further be appreciated that the filament or resistance element may be made of any desirable material, such, for example, as tungsten or a tungsten alloy when it is used in connection with incandescent lamps.

From the foregoing, it is apparent that I have provided a novel filament or resistance arrangement and a novel lamp element wherein a multi-filament arrangement is provided at only a negligible increase in cost over a single-filament arrangement. It will also be appreciated that I have provided a new and novel method for making a lamp element which is extremely economical to practice and results in a very highly efficient element.

It will, of course, be understood that numerous details of construction may be varied through a wide range without departing from the principles of this invention, and it is therefore not the purpose to limit the patent granted hereon otherwise than is necessitated by the scope of the appended claims.

I claim as my invention:

1. In an incandescent lamp element, a pair of spaced lead-in wires each having an integral end portion shaped to provide a pair of bendable clamping parts, and an integral triple segmented filament with each end and each point between adjacent segments thereof clamped in a different one of said parts.

2. The method of making a resistance element, including the steps of winding a coil, skipping a turn at two spaced points to define three connected coil segments, and shaping the winding substantially into a loop with two segments forming the loop and the third segment extending across the loop.

3. The method of making a resistance element, including the steps of winding a coil, skipping a turn at two spaced points to define three connected coil segments, and shaping the winding substantially into a loop with two segments

forming the loop and the third segment extending across the loop, electrically connecting each free end of the winding to the adjacent portion where a turn was skipped, and connecting a conductor to each connection between a free coil end and the portion where a turn was skipped.

4. The method of making a resistance element, including the steps of winding a coil, skipping a turn at a predetermined point to define two coil segments, and attaching a third coil segment to the connected two segments in a manner to provide a substantially closed loop of two segments with another segment extending thereacross.

15 5. The method of making a lamp element, including the steps of winding an integral filament coil with all turns in the same direction, skipping a turn at spaced intervals to provide equal coil segments, providing a pair of lead-in wires, and attaching one free end of the filament coil to one lead-in wire, attaching the next portion between segments to the other wire, attaching the next portion between segments to the first wire, and proceeding thus until the other free end is attached to one of the wires.

20 6. The method of making a lamp element, including the steps of bending the ends of a pair of lead-in wires to provide a pair of adjacent and integral clamping portions on each wire, forming an integral triple segmented filament, clamping a free end of the filament in one of said portions on one wire, the next space between segments in a portion on the other wire, the next such space in the other portion of the first wire, and the 25 final free end to the other portion of the other wire.

30 7. The method of making a multi-filament lamp element, including the steps of forming a segmented filament, bending the end of each of a pair of lead-in wires to provide a plurality of clamping portions in different planes, and clamping an end of the filament to one wire, the next space between segments to the other wire, and alternating thus between the wires until the final 35 end of the filament is clamped.

40 8. The method of making a multi-filament lamp element, including the steps of bending an end of a lead-in wire to provide a laterally extending clamping portion and a vertically extending clamping portion, providing another similarly shaped lead-in wire spaced from the first wire, and alternately clamping a segmented filament at spaced points first to one wire and then the other.

55 9. In an incandescent lamp element, a pair of spaced lead-in wires each arranged to provide a plurality of clamping portions, and a filament with its ends and spaced intermediate points each held in a different clamping portion.

60 10. In an incandescent lamp element, a pair of spaced lead-in wires each having a lateral U-bend and a vertical U-bend to provide a pair of compressible clamping parts, and an elongated filament disposed with its ends and certain intermediate points each clamped in a different one of said parts.

70 11. In an incandescent lamp element, a pair of spaced lead-in wires each having a lateral U-bend and a vertical U-bend to provide a pair of compressible clamping parts, the lateral bends extending in opposite directions and the vertical bends having their free sides oppositely disposed and an elongated filament disposed with its ends and certain intermediate points each clamped in a different one of said parts.

12. The method of making a multi-filament lamp element, including the steps of bending the ends of a pair of lead-in wires to provide a plurality of adjacent clamping portions on each wire, and clamping an end of a filament in a portion of one wire, an intermediate point in a portion of the other wire, and alternating thus between the wires until the final end of the filament is clamped.

13. The method of making a multi-filament lamp element, including the steps of shaping a pair of lead-in wires to provide a plurality of clamping portions on each wire, and alternately clamping a filament at spaced points first to one wire and then the other until the filament is clamped a plurality of times to each wire.

CHESTER H. FULP.
